UNITED STATES PATENT OFFICE.

GEORGE ABNER TURNER, OF ROANOKE, VIRGINIA.

SASH-FASTENER.

SPECIFICATION forming part of Letters Patent No. 592,070, dated October 19, 1897.

Application filed November 28, 1896. Serial No. 613,813. (No model.)

To all whom it may concern:

Be it known that I, GEORGE ABNER TURNER, a citizen of the United States, residing at Roanoke, in the county of Roanoke and State of Virginia, have invented certain new and useful Improvements in Sash-Locks; and I do declare the following to be a full, clear, and exact description of the invention, such as will enable others skilled in the art to which it appertains to make and use the same.

My invention has relation to improvements in sash-locks, and the object is to provide a simple, durable, and effective lock for this purpose; and to this end the novelty consists in the construction, combination, and arrangement of the same, as will be hereinafter more fully described, and particularly pointed out in the claim.

In the accompanying drawings the same reference-numerals indicate the same parts of the invention.

Figure 1 is a front elevation of my improved sash-lock with the same unlocked. Fig. 2 is a similar view with the sash locked. Fig. 3 is a bottom end view. Fig. 4 is a front elevation with the locking-lever removed. Fig. 5 is a reverse view of the locking-lever, and Fig. 6 is a vertical section of the complete sash-lock.

1 represents a sheet-metal plate formed with parallel guide-flanges 2 2'.

3 represents the rectangular sash-bolt, which has a horizontal movement between the guide-flanges. The face of this bolt is formed with 35 a dovetail recess 4, in which is detachably secured a leather or other flexible cushion-jaw 5, as shown in Fig. 1. This form is in-

tended for use on highly finished or polished woodwork in the better class of offices or residences, while for factories, offices, and ordinary dwellings a metal jaw 5', formed with a serrated face, is employed, as shown in Fig. 4. This bolt 3 is provided with an oval vertical recess 6, which receives the cam or eccentric 7, formed integral with the inner face 45 of the lever 8, which is fulerumed on the screw 9. The lever 8 is provided with an integral flange 10, which projects over the face of the recess 6 to prevent the entrance of dust and dirt.

The outer edge of the flange 2' is formed with an integral spring-dog 12, which automatically engages the handle of the lever when the bolt has been shot to lock the sash.

Having thus fully described my invention, 55 what I claim as new and useful, and desire to secure by Letters Patent of the United States, is—

A sash-lock comprising the plate 1 having the parallel guide-flanges 2 2', the latter being 60 formed with an integral spring-dog 12, the rectangular bolt 3 formed with a dovetail recess 4 carrying a removable jaw, and the oval vertical recess 6, in combination with the lever 8 having integral cam 7 and flange 10, and the 65 fulerum-screw 9, substantially as shown and described.

In testimony whereof I hereunto affix my signature in presence of two witnesses.

GEORGE ABNER TURNER.
